UNITED STATES PATENT OFFICE.

RAY C. HIMEBAUGH, OF BURR OAK, MICHIGAN, ASSIGNOR TO ADELBERT C. HIMEBAUGH, OF BURR OAK, MICHIGAN.

HAND-PLANTER.

1,153,225.

Specification of Letters Patent. Patented Sept. 14, 1915.

Application filed October 5, 1914. Serial No. 865,074.

To all whom it may concern:

Be it known that I, RAY C. HIMEBAUGH, a citizen of the United States residing at Burr Oak, Michigan, have invented certain new and useful Improvements in Hand-Planters, of which the following is a specification.

This invention relates to improvements in hand planters.

10 My improvement relates particularly to hand planters adapted for use as potato planters although certain features are capable of embodiment and desirable for use in other forms of hand planters such as corn planters.

15 The main objects of this invention are: First,—to provide an improved hand planter in which the several parts are simple and economical to produce and are easily 20 and quickly assembled and when assembled provide a structure which is rigid and durable although comparatively light in weight.

Second,—to provide in a hand planter an improved hopper structure.

25 Further objects, and objects relating to structural details, will definitely appear from the detailed description to follow.

I accomplish the object of my invention by the devices and means described in the 30 following specification.

The invention is clearly defined and pointed out in the claims.

35 A structure which is a preferred embodiment of my invention is clearly illustrated in the accompanying drawing forming a part of this specification, in which:

40 Figure I is a front perspective view of a hand planter embodying the features of my invention. Fig. II is a detailed rear perspective view of the lower portion of the planter. Fig. III is a horizontal section on a line corresponding to line 3—3 of Fig. II. Fig. IV is a detail section on a line corresponding to line 4—4 of Fig. I. Fig. 45 V is a detail section on a line corresponding to the broken line 5—5 of Fig. I. Fig. VI is a detail section on a line corresponding to line 6—6 of Fig. I showing details of the connection for the spring to the movable 50 blade.

In the drawing similar reference characters refer to similar parts throughout the several views, and the sectional views are

taken looking in the direction of the little arrows at the ends of the section lines.

55

Referring to the drawing, I provide a staff 1 which is channel shape in cross section. The fixed blade 2 is provided with a socket plate extension 3 on its upper edge. A socket member 4 having a channel 5 there- 60 in adapted to receive the lower end of the staff is secured to the rear side of the plate 3 by means of rivets 6. This socket member has an extension 7 lapping the rear side of the blade 2 and secured thereto by rivets 65 6 so that it constitutes a reinforcing member for the blade at this point. A foot rest 8 projects from the side of the blade 2. This foot rest 8 is provided with a flange 9 which is arranged under the extension 7 of the 70 socket member 4 and secured by the rivets 6 by means of which the extension is secured to the fixed blade 2.

The fixed blade 2 is provided with forwardly projecting flanges 10 on its side 75 edges. The movable blade 11 has rearwardly projecting flanges 12 which embrace and are pivoted to the flanges 10 of the fixed blade by the pivots 13. A stop 14 limits the swing of the pivoted blade. The 80 pivoted blade is provided with a forwardly projecting foot 15 having a pair of spaced ears formed thereon, see Fig. I.

The hopper 17 is formed of a sheet of metal rolled into cylindrical form with its 85 edges overlapping and disposed against the front side of the staff, the lower end of the hopper being disposed within the flanges of the blades 2 and 11. The hopper is provided with a flaring rim or top member 18 90 which is formed of a strip of metal bent into a ring with its ends overlapping. The top member 18 is arranged within the top of the hopper. This top member is formed of material considerably heavier than the 95 material of the hopper and serves to protect and support it as well as providing a flaring mouth therefor. These parts are secured together by bolts 19 and 20, the bolt 19 being arranged through the lapped edges of the 100 hopper, the socket members 3 and 4 and the staff, see Fig. III.

The bolt 20 is arranged through the lapped ends of the top member 18, the lapped edges of the hopper and the staff, see Fig. V. 105

The handle 21 is provided with shank

portions 22 which are disposed on the sides of the shaft and secured by a bolt 23. The staff has a plurality of holes 24 for this bolt 23 so that the handle may be adjusted on 5 the staff.

The pivoted blade is yieldingly held in its closed position by means of the bow spring 25 which is formed of wire and has a central spring coil 26. The lower end of 10 the spring has an eye 27 which is engaged by the pin 28 arranged through the eyes 16. The upper end of the spring has a socket engaging portion 29 which engages the loop or socket strap 30 secured on the 15 front side of the hopper. This securing means for the spring supports it in proper position, that is the ears prevent the spring swinging out of place as well as provide a satisfactory connection therefor to the pivoted blade.

The upper end of the spring may be engaged or disengaged with the socket 30.

My improved planter is simple and economical in its parts and is easily assembled 25 and when assembled is strong and rigid.

I have illustrated and described my improvements in the form in which I have embodied the same in practice.

I have not attempted to illustrate or describe certain modifications which I contemplate as I believe the disclosures made will enable those skilled in the art to which my invention relates to embody or adapt the same as the conditions may require.

Having thus described my invention, what I claim as new and desire to secure by Letters Patent, is:

1. In a hand planter, the combination of 40 a staff, a fixed blade having forwardly projecting flanges at its side edges and an upwardly projecting socket plate extension on its upper edge, a socket member channeled to receive the lower end of said staff secured to the rear side of said socket plate and extended onto the rear side of said blade and constituting a reinforcing member therefor, a movable blade having rearwardly projecting flanges on its side edges pivoted on the forwardly projecting flanges 45 of said fixed blade, a hopper formed of sheet metal rolled into a cylinder with lapped edges disposed on the side of said staff, a flaring top member formed of a strip of metal bent into a ring with its ends lapping, said top member disposed within the upper end of said hopper with its lapped ends over the lapped edges of said hopper, a bolt arranged through the lapped edges of said hopper 50 said staff socket members and staff, and a bolt disposed through the lapped ends of said top member and the lapped edges of said hopper and said staff.

2. In a hand planter, the combination of 60 a staff, a fixed blade having forwardly pro-

jecting flanges at its side edges and an upwardly projecting socket plate extension on its upper edge, a socket member channeled to receive the lower end of said staff secured to the rear side of said socket plate and extended onto the rear side of said blade and constituting a reinforcing member therefor, a movable blade having rearwardly projecting flanges on its side edges pivoted on the forwardly projecting flanges of said fixed blade, a hopper of sheet metal rolled 70 into a cylinder with lapped edges disposed on the side of said staff, and a bolt arranged through the lapped edges of said hopper said staff socket members and staff.

3. In a hand planter, the combination of 80 a staff, a fixed blade having an upwardly projecting socket plate extension on its upper edge, a socket member channeled to receive the lower end of said staff secured to the rear side of said socket plate and extended onto the rear side of said blade and constituting a reinforcing member therefor, a hopper formed of sheet metal rolled into 85 a cylinder with lapped edges disposed on the side of said staff, a flaring top member 90 formed of a strip of metal bent into a ring with its ends lapping, said top member disposed within the upper end of said hopper with its lapped ends over the lapped edges of said hopper, a bolt arranged through the lapped edges of said hopper 95 said staff socket members and staff, and a bolt disposed through the lapped ends of said top member and the lapped edges of said hopper and said staff.

4. In a hand planter, the combination of 100 a staff, a fixed blade having an upwardly projecting socket plate extension on its upper edge, a socket member channeled to receive the lower end of said staff secured to 105 the rear side of said socket plate and extended onto the rear side of said blade and constituting a reinforcing member therefor, a hopper formed of sheet metal rolled into a cylinder with lapped edges disposed on 110 the side of said staff, and a bolt arranged through the lapped edges of said hopper said staff socket members and staff.

5. A hand planter comprising a staff, a 115 fixed blade provided with a socket for said staff, a hopper formed of sheet metal rolled into a cylinder with lapped edges disposed on the side of said staff, a flaring top member formed of a strip of metal bent into a ring with its ends lapping, said top member disposed within the upper end of said hopper with its lapped ends over the lapped edges of said hopper, a bolt arranged 120 through the lapped edges of said hopper said staff socket and staff, and a bolt disposed through the lapped ends of said top member and the lapped edges of said hopper and said staff, said bolts constituting the 125

means for securing the lapped edges of said hopper and the lapped ends of said top member together.

6. A hand planter comprising a staff, a fixed blade provided with a socket for said staff, a hopper formed of sheet metal rolled into a cylinder with lapped edges disposed on the side of said staff, and a bolt arranged through the lapped edges of said hopper, 5 said staff socket and staff, said bolt constituting the means for securing the lapped edges of said hopper together.

7. A hand planter comprising a staff, a fixed blade, a pivoted blade, a hopper 15 formed of sheet metal rolled into a cylinder with lapped edges disposed on the side of said staff, a flaring top member formed of a strip of metal bent into a ring with its ends lapping, said top member disposed within 20 the upper end of said hopper with its lapped ends over the lapped edges of said hopper, and bolts arranged through the lapped edges of said hopper and through the lapped ends of said top member and the 25 lapped edges of said hopper and said staff, said bolts constituting the means for securing the lapped edges of said hopper and the lapped ends of said top member together.

8. A hand planter comprising a staff, a 20 hopper formed of sheet metal rolled into a cylinder with lapped edges disposed on the side of said staff, a top member formed of a strip of metal bent into a ring with its

ends lapping, said top member being disposed within the upper end of said hopper 35 with its lapped ends over the lapped edges of the hopper and with its upper edge projecting from the hopper and bolts arranged through the lapped ends of said top member, and the lapped edges of said hopper 40 and said staff, said bolts constituting the means for securing the lapped edges of said hopper and the lapped ends of said top member together and for securing said top member and hopper to said staff. 45

9. A hand planter, comprising a staff, a fixed blade secured to said staff, a pivoted blade, a forwardly projecting foot on said pivoted blade, said foot being provided with a pair of spaced ears, a bow spring, 50 having an eye at its lower end disposed between said ears of said foot member and secured thereto by a pin through the ears engaging said eye, and a socket with which the upper end of said spring is engaged, 55 said spring being prevented from turning in its socket and being supported against lateral swinging movement by the engagement of its said eye with said ears.

In witness whereof, I have hereunto set 60 my hand and seal in the presence of two witnesses.
